UNITED STATES PATENT OFFICE.

EDWARD C. BOYNTON, OF NEWBURGH, NEW YORK.

ELECTRIC RAILWAY.

SPECIFICATION forming part of Letters Patent No. 732,512, dated June 30, 1903.

Application filed March 5, 1903. Serial No. 146,419. (No model.)

To all whom it may concern:

Be it known that I, EDWARD C. BOYNTON, a citizen of the United States, residing at Newburgh, county of Orange, and State of New York, have made a new and useful Invention in Electric Railways, of which the following is a specification.

My invention is directed particularly to improvements in electric railways where the propelling-motors of the cars or trains are supplied by currents taken from live working conductors—such, for instance, as are known in the art as of the "third-rail" or "trolley" type; and it has for its object to provide a simple and efficient means of supplying such current to the motors of cars or trains in car-yards or in places where there is a number of parallel tracks.

Heretofore it has not been practical to utilize electric railways of the third-rail or trolley type in places where there are numbers of parallel tracks and crossing-tracks from one line to another and branching from one or more main-line tracks having either overhead or third-rail trolley-conductors parallel therewith—such, for instance, as are found in car-yards where cars are switched from one line of tracks to another—owing to the fact that by reason of the crossing and intercrossing of the lines of track or service rails there is offered great danger of short-circuiting of the currents from the third rails. Furthermore, such a multiplicity of third rails necessarily increases the danger to employees and other persons passing through or working in the yards.

My invention is designed to afford a simple and efficient means of avoiding these objectionable features; and to this end it consists, broadly, in combining with existing types of trolley or third-rail systems which are provided with a number of branching parallel lines or tracks at the desired points a series of branch feeders or contacting conductors extending across or over the several parallel lines of track or service rails at definite intervals and supported by beams or timbers upon posts at their opposite ends or wholly from an overhead means of support, the arrangement being such that the current may be supplied to the motors from an underrunning trolley shoe or skate adapted to bridge

the space between any two or more of such branch feeders or contacting conductors as the car or train passes over or by the end of 55 the trolley-conductor or third rail when being switched or transferred from the main track or tracks or when continuing on its direct course. In other words, my invention embraces the existing well-known types of 60 trolley or third-rail systems, in which the current is conveyed to a motor or motors on the cars thereof by a current-collector, shoe, or trolley adapted to bear under or against the trolley-conductor or upon the third rail when 65 in use upon a main line, in combination with contacting cross-conductors located over the roadway and all of a series of branch tracks or lines, said contacting conductors being so located as to allow the cars and their supported trolley shoes or skates to move freely 70 in all directions when being switched from track to track.

My invention will be fully understood by referring to the accompanying drawings, in 75 which—

Figure 1 is a plan view illustrating one manner of applying the invention, and Fig. 2 is a longitudinal sectional view taken through Fig. 1 on a line parallel with the main line of 80 track-rails.

Referring now to the drawings in detail for a full and clear understanding of the invention, such as will enable others skilled in the art to construct and use the same, and first 85 to Fig. 1, T T represent a single or main line of track or service rails entering a car-yard wherein are located several parallel sets of track or service rails T' T² T³ T⁴ T⁵ and what are known as "crossing" track-rails T⁶ T⁷ 90 for enabling cars or trains to be transferred from any one line of rails to another.

TR is a third rail for conveying electrical current to the motors on the cars when on the main track, said third rail being located, as 95 is usual, outside and parallel with one of said lines of rail.

F' is a current-feeder connected either to the third rail TR or to an independent source of electrical energy and electrically connected to a series of branch feeders in the nature of steel trusses or I-beams F² F³ F⁴, &c., supported and insulated from posts P' P², P³ P⁴, P² P³, P⁴ P⁵, &c., said branch feeders

being located at definite intervals and preferably at an equal distance above the level of the tracks, so that their lower surfaces are on substantially the same level, as clearly 5 illustrated in Fig. 2. In place of metal I-beams $F^2 F^3 F^4$, &c., wooden or other stringers might be substituted therefor with flat copper conductors secured to the under surface thereof in any preferred manner and 10 connected directly to the feeder F' , as will be readily understood by those skilled in the art.

C represents an electric locomotive of well-known form, provided with the usual trucks, as shown, and contacting shoes or current-collectors S S for conveying the current from the third rail TR to the motor or motors (not shown) on board of the car.

S' is an elongated skate or contact-shoe, preferably of the same length as the car and 20 of good conducting material, said skate or shoe being pivotally secured, preferably, to two or more trolley-arms A A' A² of well-known type, two of said trolley-arms A A² being secured directly to bases carried by 25 braced supports B B' and the middle or third one A' directly upon the roof of the car or locomotive-cab. Said trolley-arms are provided with the usual springs or yielding devices for maintaining the skate or shoe S' in 30 any desired position and with the proper upward pressure and preferably such as to give to the upper surface thereof good electrical contact with the under surfaces of the branch feeders or contacting conductors 35 $F^2 F^3 F^4$, &c., as it passes thereunder. The greatest distance between any two of such branch feeders or conductors is usually slightly less than the length of the shoe or skate S' . Said trolley-shoe or skate is connected in a manner well understood directly 40 with the motors on board the cars and may be provided with the usual trolley-cord and appliances in the cab for holding it in any desired position, the arrangement being such 45 that when the lower set of trolley shoes or contacts S leave the third rail TR, as will be understood on inspection of Fig. 2, by passing from left to right the upper skate or contact-shoe S' will have underrunning electrical

50 contact with the branch feeders or contacting conductors $F^2 F^3 F^4$, &c., in sequence and the circuit to the motor or motors will never be broken. These branch feeders or conductors $F^2 F^3 F^4$, &c., as will be understood, bridge the entire width of all the tracks 55 over which they are located, so that when a car is transferred from the main-track rails T T to any other track or over any one of the crossing tracks T⁶ there will always be electrical contact between the contact-shoe or 60 skate S' and some one of the branch feeders or contacting conductors $F^2 F^3 F^4$, &c. In Fig. 2 of the drawings I have shown how this same trolley-shoe or skate S' may be used 65 with a service or working conductor T' R' for the main track. In this instance a wooden or other insulating stringer is provided and

secured to cross ties or beams with a feeder or conductor similar to TR and on a level with the lower surface of the feeders or conductors $F^2 F^3 F^4$, said working conductor being in the nature of an inverted steel or other metal trough, such as is well known in the art, the arrangement being such that when the trolley-shoe or skate leaves the last branch 70 feeder F^2 in passing from right to left it will come into electrical contact with the service or working conductor T' R' and maintain electrical connection therewith.

While I have shown the branch feeders or 80 conductors $F^2 F^3 F^4$, &c., as being in the nature of steel I-beams supported upon posts, they may be supported in any other preferred manner—as, for instance, by trusses sustained at their opposite ends from pillars 85 or posts or on walls, or where the service or track rails are located in a building, as in union depots, said conductors may be supported directly from the trusses of the building, such manner of support being well known 90 and within the skill of the engineer, my invention being directed, broadly, to the arrangement of branch feeders or conductors over the tracks and in such manner that the working current may be supplied to the motors upon the cars as they pass thereunder and no matter upon which one of a series of substantially parallel tracks a car or train propelled by said motor or motors may be traveling.

I wish it distinctly understood that my 100 claims are of the most generic nature as to the combination of means for supplying current to an electrically-propelled motor car or train when passing either over a main track having a contacting trolley-conductor or third rail parallel therewith or any one of a series of parallel tracks branching therefrom through the agency of cross branch feeders supported above the parallel tracks and in 110 such manner that there is no danger to employees or other persons passing over the tracks in the yard or building or other places where such lines of parallel tracks may be located, and my claims are generic as to such 115 features.

I am aware that prior to my invention an electric railway had been devised in which the current supplied to the motor on the cars was conveyed thereto by overhead cross-conductors extending over a main track and a branch track and supported upon posts on the opposite sides of each track or each branch track, and I make no claim hereinafter broad enough to include such a structure, my most 120 generic claim in this particular being to a series of cross-conductors which extend continuously across a series of tracks, so that a car provided with an upwardly-bearing skate or shoe may swing from one track to another 125 and maintain the contact between the shoe and the cross-conductors without interrupting the circuit to the motors on board the same, the cross-conductors being so supported 130

that the lateral movement of the cars in being switched from track to track is not interfered with.

Having thus described my invention, what I claim, and desire to secure by Letters Patent of the United States, is—

1. A railway system embracing a main-line track, a contacting trolley-conductor or third rail parallel therewith and extending over the route; in combination with two or more parallel tracks branching therefrom and a series of overhead contacting conductors extending entirely across all of said tracks and electrically connected to a source of electrical energy, together with means for supporting said conductors in such manner that the lateral movement of the cars in being switched from track to track is not interfered with, substantially as described.
2. In an electric-railway system a main-line track and a contacting trolley-conductor or third rail therefor extending over the route and parallel therewith; in combination with a series of substantially parallel tracks branching therefrom and a series of overhead contacting conductors extending entirely across all of said tracks and electrically connected to a source of electrical energy; together with means for supporting said conductors in such manner that the lateral movement of the cars in being switched from track to track is not interfered with, substantially as described.
3. In an electric-railway system a main-line track and a contacting trolley-conductor or third rail therefor extending entirely over the route and parallel therewith; a series of substantially parallel tracks branching from the main-line track; a series of crossing tracks for transferring cars from any one of said parallel tracks to another; in combination with a series of overhead conductors extending entirely across all of said tracks and electrically connected to a source of electrical energy; together with means for supporting said conductors in such manner that the lateral movement of the cars in being switched from track to track is not interfered with.
4. In an electric-railway system a main-line track and a contacting trolley-conductor or third rail therefor extending entirely over the route and parallel therewith; in combination with a series of substantially parallel tracks branching from the main-line track; a series of overhead contacting conductors extending entirely across all of said tracks and located at substantially the same height therefrom; together with means for supporting the same in such manner that the lateral movement of the cars in being switched from track to track is not interfered with; said conductors being connected to a source of electrical energy, substantially as described.
5. In an electric-railway system a main-line track and a contacting trolley-conductor or third rail therefor extending entirely over the route and parallel therewith; a series of sub-

stantially parallel tracks branching from the main-line track; a series of overhead contacting conductors extending entirely across all of said tracks and electrically connected to a source of electrical energy; in combination with means for supporting said conductors in such manner that the lateral movement of the cars in being switched from track to track is not interfered with; together with a motor-car or electric locomotive having a contacting shoe or skate adapted to bridge the space between any two or more conductors, said shoe or skate being electrically connected to a motor or motors on board the car or locomotive, substantially as described.

6. An electric-railway system embracing one or more main-line tracks; one or more parallel third rails or contacting conductors therefor extending entirely over the route and a series of tracks branching from the main-line track or tracks; in combination with a series of branch feeders or contacting conductors extending entirely over all of said tracks; together with means for supporting said conductors, substantially as described.

7. An electric-railway system embracing a main-line track; a series of tracks branching therefrom and a third rail or contacting conductor therefor; in combination with a series of tracks branching from the first-named track and a series of branch feeders or contacting conductors extending entirely across or over all of said tracks; together with means for supporting said conductors, substantially as described.

8. An electric-railway system embracing one or more main-line tracks; one or more third rails or contacting conductors parallel therewith and connected to a source of electrical energy; in combination with a series of tracks branching from the first-named track or tracks and a series of continuous overhead contacting conductors located above said tracks at right angles thereto, said conductors offering continuous contacting surfaces from end to end over the entire series of tracks and electrically connected with a source of electrical energy; together with one or more motor-cars or electric locomotives provided with a contacting shoe or skate adapted to bridge the space between any two or more of said overhead conductors, the arrangement being such that any car or train may be switched from the main-line track to any one of the branch tracks without interrupting the current to the motors and without offering obstruction to the lateral movement thereof, substantially as described.

In testimony whereof I have signed my name to this specification in the presence of two subscribing witnesses.

EDWARD C. BOYNTON.
